DESIGN FOR A COMBINED KEY RING AND FLASHLIGHT

Irving Florman, New York, N. Y.

Application August 11, 1938, Serial No. 79,274

Term of patent 14 years

To all whom it may concern:

Be it known that I, Irving Florman, a citizen of the United States, residing at New York, in the county of New York and State of New York, have invented a new, original, and ornamental Design for a Combined Key Ring and Flashlight, of which the following is a specification, reference being had to the accompanying drawing, forming a part thereof.

In the drawing:

Fig. 1 is a side elevation of the combined key ring and flashlight, showing my new design;

Fig. 2 is an end view of the flashlight shown in Fig. 1.

I claim:

The ornamental design for a combined key ring and flashlight, substantially as shown.

IRVING FLORMAN.
